UNITED STATES PATENT OFFICE.

WILLIAM MUIR ANDREWS, OF GLASGOW, SCOTLAND.

DESIGN FOR A SHIRT-BOSOM.

SPECIFICATION forming part of Design No. 28,480, dated April 19, 1898.

Application filed December 31, 1897. Serial No. 665,245. Term of patent 7 years.

To all whom it may concern:

Be it known that I, WILLIAM MUIR ANDREWS, manufacturer, late of 217 St. George's road, but now of 21 Endeliegn Gardens, Partickhill road, Glasgow, Scotland, have invented and produced a new and original Design for Shirts, of which the following is a specification, reference being had to the accompanying drawing, illustrating my improved design.

The drawing shows a plan view of a shirt-bosom, illustrating my design.

The leading feature of my design consists of the angular extensions A on the side edges of a substantially rectangular-shaped bosom B, which gives to the bosom a characteristic and distinguishing appearance. The angular extensions are located on the side edges of the

bosom, between the upper and lower ends thereof, with their apexes projecting outward. 20

The outline of the sides of the shirt-bosom is irregular because of the angular extensions, and this gives to the bosom a distinguishing and characteristic appearance.

Having thus described my improved design, what I claim is—

The design for a shirt-bosom, substantially as shown and described.

In testimony whereof I have signed my name to this specification in the presence of 30 two witnesses.

WM. MUIR ANDREWS.

Witnesses:

JOHN LIDDLE,
EDITH MARY EDMONDSTONE.
